ENGRAVING TOOL OR THE LIKE

Douglas W. Anderson, Palatine, Ill., assignor to Burgess Vibrocrafter, Inc., a corporation of Delaware

Filed May 3, 1965, Ser. No. 85,064

Term of patent 14 years

(Cl. D54—14)

FIG. 1 is a left side perspective view of an engraving tool showing my new design;

FIG. 2 is a top view thereof;

FIG. 3 is a right side elevational view;

FIG. 4 is a front view, and

FIG. 5 is a rear view thereof.

The essential features of my design reside in the portions shown in full lines.

I claim:

The ornamental design for an engraving tool or the like, substantially as shown and described.
